UNITED STATES PATENT OFFICE

RAY P. ROSENBERRY, OF CLEVELAND, OHIO, ASSIGNOR TO THE SILVER KING HYDRAULIC JACK COMPANY, OF CLEVELAND, OHIO, A CORPORATION OF OHIO

HYDRAULIC JACK

Application filed April 7, 1930. Serial No. 442,117.

This invention relates to hydraulic jacks, and has for its principal object the provision of an improved jack of this type. In the drawing accompanying this specification, and forming a part of this application, I have shown, for purposes of illustration, one form which my invention may assume, and in this drawing:

Figure 1 is a vertical sectional view of an embodiment of a hydraulic jack, portions of the stuffing box construction being shown in elevation, while

Figure 2 is an enlarged vertical sectional view through the stuffing box arrangement and showing the cooperating parts in vertical section.

The present invention is directed more particularly to the manner of mounting the ram of the hydraulic jack, and the disclosure has been restricted to this construction; for an understanding of the complete jack construction reference is made to applicant's companion application filed of even date herewith, and which fully discloses the operation and construction of the hydraulic jack to which the present invention relates.

In the embodiment of the invention set forth in the drawing the jack comprises a reservoir 10, and a ram cylinder 11, both cast integrally with a supporting base member 12. Mounted in the cylinder 11 is a ram 13 which extends upwardly through a stuffing box arrangement designated generally by the reference character 14, and at its upper end the ram has secured thereto a supporting member or head 15. At the upper end of the casting the cylinder 11 is provided with an annular enlargement 16 which has a threaded counter-bore 17, and an unthreaded counter-bore 18, the latter being somewhat larger than the bore of the cylinder 11, and separated therefrom by a shoulder 19.

Disposed in the counter-bore 18 so as to rest on the shoulder 19 is a ring 20, the lower face 21 of which is disposed at right angles to the axis thereof, and the upper face of which is tapered from the outer edges to the inner edges in a direction toward the face 21, to provide wedge surfaces 22. Just above

the ring 20 is a packing member 23 of suitable flexible material, having a cylindrical portion 24 of a thickness to fit tightly between the ram and the adjacent wall of the counter-bore 18, and at its lower end provided with chamfered wedge surfaces 25, corresponding substantially to the wedge surfaces 22 of the ring 20, and in operative position spaced slightly therefrom. The cylindrical portion 24 of the packing member 23 has a lateral integral flange 26, seated upon the shoulder 27 between the counter-bore 17 and counter-bore 18. Above the flange 26 of the packing member 23 there is provided a washer 28 threaded downwardly in the bore 17 tightly against the flange 26 of the packing member 23 so as to seal the flange 26 against leakage of liquid therewith. The washer 28 is disposed about the ram 13, and at its inner edges provides a bearing surface 29 for the ram 13.

Above the bearing surface 29 the inner edge of the washer 28 is tapered as indicated at 30, thereby forming a space between the adjacent surface of the portion 30 and the adjacent surface of the ram 13. In its upper face the washer 28 is provided with transversely extending grooves extending from the outer edge of the washer 28 to its inner edges, while above the washer 28 is a second washer 32, threaded downwardly in the bore 17 so as to bear tightly against the upper face of the washer 28, and cooperating with the washer 28 to form the grooves in the washer 28 into ducts 31 extending through the packing means, one of the ducts or grooves 31 communicating with the reservoir 10 through the port 33 in the upper end of the enlarged portion 16. Above the washer 32 there is provided a packing material 34, which is crushed downwardly by an adjusting nut 35 threaded into the counter-bore 17 and having a tapered face 36 for engaging and properly compressing the packing 34.

The lower end of the ram 13 is provided with a socket 37, and with a transverse duct 38 extending from the socket entirely through the outer face of the ram, while the outer surface of the ram at its lower end is provided with an annular groove accommodating a

spring ring 39 adapted to engage the under-surface 21 of the ring 20 at its upper limit of movement.

During operation of the jack, as clearly appears from my companion application above referred to, when it is desired to raise the ram 13 liquid is admitted from the reservoir 10 to the cylinder 11 causing upward movement of the ram. Immediately upon admission of liquid to the cylinder 11 a quantity of the liquid will pass up about the ram and come into contact with the under surface 21 of the ring 20; this ring being rather loosely mounted will be somewhat elevated and the wedge surfaces 22 thereof acting upon the wedge surfaces 25 of the packing member 23, will wedge the portion 24 of the packing member tightly against the ram surfaces, operating to prevent leakage of liquid past the adjacent surfaces of the portion 24 of the packing member and the surfaces of the ram with which they are engaged. Any liquid passing upon the outside of the packing member 23 will also tend to press the portion 24 tightly against the ram, and leakage of liquid past the flange 26 of the packing member 23 is at least substantially prevented due to the tight clamping of the flange 26 between the shoulder 27 and the washer 28. Any liquid escaping past the packing member 23 will accumulate in the chamber provided by the tapered surfaces 30 of the washer 28, and will escape to the reservoir through the duct 31 communicating with the port 33 returning to the reservoir. When the ram 13 reaches its uppermost position any additional liquid admitted to the cylinder 11 will pass through the socket 37, and the duct 38, and will be returned to the reservoir 10 through the duct 31 and port 33, thereby preventing injurious pressure being applied to the ram.

From the above description it will be obvious to those skilled in the art that the invention provides a new and improved hydraulic jack. At the same time those skilled in the art will appreciate that the embodiment of my invention herein shown and described may be used for other purposes than those specifically pointed out or suggested, and embodies advantages and uses other than those specifically pointed out or suggested herein, and also that this particular embodiment of my invention herein described may be variously changed and modified, without departing from the spirit of my invention, or sacrificing the advantages thereof, wherefore it will be understood that the disclosure herein is illustrative only, and that my invention is not limited thereto.

60 I claim:

1. A hydraulic jack, comprising: a reservoir; a ram cylinder having an internally screw threaded recess in the upper portion thereof forming a first shoulder, said ram cylinder also having an outlet passage for

establishing communication between said reservoir and said recess, and having a second shoulder disposed therein below said first shoulder; a ram disposed within said ram cylinder and having a radially extending passage formed in the lower portion thereof communicating with the ram cylinder beneath said ram; an annular member surrounding said ram in spaced relation therewith in seating engagement with said second shoulder and having an inwardly and downwardly inclined upper surface; a first packing member surrounding said ram and having an annular flange disposed in seating engagement with said first shoulder and with an inwardly and downwardly inclined lower surface for operative engagement with the correspondingly inclined upper surface of said annular member; a first washer surrounding said ram in threaded engagement with the threads of said recess for maintaining said packing member in sealing engagement with said ram, said washer having a beveled inner circumference and radially extending grooves in the upper face thereof; and a second washer surrounding said ram in screw threaded engagement with the threads of said recess for engagement with said first washer to close the beveled portion thereof and said grooves, and forming therewith an inner annular passage intersected by radially extending passages, the passage in the lower portion of said ram being adapted to communicate with said annular passage and with said radial passages when said ram reaches its upper limit of travel to permit the escape of fluid from said ram cylinder to said reservoir through said outlet passage.

2. A hydraulic jack, comprising: a reservoir; a ram cylinder having an internally screw threaded recess in the upper portion thereof forming a first shoulder, said ram cylinder also having an outlet passage for establishing communication between said reservoir and said recess, and having a second shoulder disposed therein below said first shoulder; a ram disposed within said ram cylinder and having a radially extending passage formed in the lower portion thereof communicating with the ram cylinder beneath said ram; an annular member surrounding said ram in spaced relation therewith in seating engagement with said second shoulder and having an inwardly and downwardly inclined upper surface; a first packing member surrounding said ram and having an annular flange disposed in seating engagement with said first shoulder, and with an inwardly and downwardly inclined lower surface for operative engagement with the correspondingly inclined upper surface of said annular member; a first washer surrounding said ram in threaded engagement with the threads of said recess for maintaining said packing member in sealing engagement with said ram cylinder.

ment with said ram, said washer having a beveled inner circumference and radially extending grooves in the upper face thereof; a second washer surrounding said ram in screw threaded engagement with the threads of said recess for engagement with said first washer to close the beveled portion thereof and said grooves, and forming therewith an inner annular passage intersected by radially extending passages communicating with said outlet passages; a second packing member surrounding said ram; and a member threaded into said recess above said second packing member for compressing the same against said second washer and against said ram, the passage in the lower portion of said ram being adapted to communicate with said annular passage and with said radial passages when said ram reaches its upper limit of travel to permit the escape of fluid from said ram cylinder to said reservoir through said outlet passage.

In testimony whereof I hereunto affix my signature.
